HA0103048200—Packaging Bottle, Nikkei Design, Jul. 1, 1989,
(Japanese Design Classification FA-510ADA), 1 page.
(Continued)*Primary Examiner* — Janice Patyk*(74) Attorney, Agent, or Firm* — Fitch, Even, Tabin &
Flannery LLP(57) **CLAIM**

The ornamental design for a bottle, as shown and described.

DESCRIPTIONFIG. 1 is a bottom front perspective view of a bottle
according to our new design;

FIG. 2 is top rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof; and,

FIG. 8 is a top plan view thereof.

The broken lines in the figures illustrate the portions of the
bottle that form no part of the claimed design.**1 Claim, 8 Drawing Sheets**| (56)	References Cited
